UNITED STATES PATENT OFFICE.

JOSEPH P. BODENMILLER, OF ST. LOUIS, MISSOURI, ASSIGNOR TO THE MENGEL COMPANY, OF LOUISVILLE, KENTUCKY, A CORPORATION OF NEW JERSEY.

DESIGN FOR A SEESAW.

58,130.

Specification for Design. Patented June 14, 1921.

Application filed March 7, 1921. Serial No. 450,492. Term of patent 14 years.

To all whom it may concern:

Be it known that I, JOSEPH P. BODENMILLER, a citizen of the United States, residing at St. Louis, State of Missouri, have invented a new, original, and ornamental Design for a Seesaw, of which the following is a specification, reference being had to the accompanying drawing, forming part thereof,

Figure 1 is a perspective view; and Fig. 2 an end elevation of a see-saw on an enlarged scale, showing my new design.

I claim.

The ornamental design for a seesaw, as shown.

JOSEPH P. BODENMILLER.
